of Buffalo, New York.

Letters Patent No. 1207, Dated Feb. 21, 1860.

The schedule referred to in these Letters Patent and making part of the same.

To all whom it may concern:

Be it known that we Henry S. Hubbell, of the City of Buffalo County of Erie and State of New York, and Thomas H. Wood & John E. Roberts of the City of Utica, County of Oneida and State aforesaid, have invented or produced a new or original design for a heating Stove called the Rosette or Heavy Plate, and we do hereby declare that the following is a full and exact description of the same, reference being had to the accompanying Photograph.

Figure 1, is a perspective view of the stove.

Letter A, is the top plate, B. B. forming together one of the sides of the stove C, the front plate and D, the door the last two pieces together forming the front, E, the bottom plate.

What we claim as our invention or production and desire to secure by Letters Patent, is the general design and configuration represented in the accompanying Photograph.
